CLAIM

We claim the ornamental design for a trigger handle, as shown and described.

DESCRIPTION

FIG. 1 is a first perspective view of a trigger handle;

FIG. 2 is a second perspective view thereof;

FIG. 3 is a front view thereof;

FIG. 4 is a rear view thereof;

FIG. 5 is a first side view thereof;

FIG. 6 is a second side view thereof;

FIG. 7 is a top side view thereof; and,

FIG. 8 is a bottom side view thereof.

Broken lines seen in the drawings depict portions of the trigger handle that form no part of the claimed design.
